(57) **CLAIM**

The ornamental design for a portion of a portable computer device, as shown and described.

DESCRIPTION

FIG. 1 is a top view of a portion of a portable computer device showing our new design; and,

FIG. 2 is a perspective view thereof.

The broken line showing of various regions within the claimed portion and the remainder of the computing device are for illustrative purposes only and form no part of the claimed design.

1 Claim, 2 Drawing Sheets

FIG. 1

FIG. 2
